UNITED STATES PATENT OFFICE.

JOSEPH PRIMBS, OF POCATELLO, IDAHO, ASSIGNOR TO GEO. PRIMBS & SONS, OF POCATELLO, IDAHO.

BANKING-FORM.

1,371,573.

Specification of Letters Patent. Patented Mar. 15, 1921.

Application filed August 12, 1920. Serial No. 403,066.

To all whom it may concern:

Be it known that I, JOSEPH PRIMBS, a citizen of the United States, residing at Pocatello, in the county of Bannock and State of Idaho, have invented certain new and useful Improvements in Banking Forms; and I do hereby declare the following to be a full, clear, and exact description of the invention, such as will enable others skilled in the art to which it appertains to make and use the same.

My invention relates to means for the simplification of banking methods and consists of an improved key numbered blank 15 or form to be used in connection with dishonored checks, or checks which are returned by a bank unpaid for one reason or another.

In order that my invention may be clearly understood, I have described the same in the following specification, reference being had to the accompanying drawing, and pointed out more specifically in the appended claims.

My improved form is provided with a delineated space in which there is printed a 25 number of possible reasons why a check, which has been presented to a bank or depository for payment, has been dishonored, and each reason is given a key number.

There is also a space provided preferably 30 at the top of the form, for the insertion of the name of the bank using the form, and a dating space, while above the space in which are contained the reasons for the return of the check unhonored, there is preferably 35 printed the legend "We charge your account and return herewith unpaid" and immediately below the same the words "Key to reason for return."

Below the list of the keyed reasons for 40 return, is a delineated space for the insertion of the name of the person or concern to whom the return is directed.

Referring to the drawings:—

Figure 1 is a plan view of my improved 45 form, provided with a tearing line and adapted to be used in returning checks to corresponding banks, and

Fig. 2 is a similar view of the form, without the tearing line, and to be used by an 50 original depository in advising a customer.

In the drawing, A represents a space in which appear the possible reasons for the return of a check, each reason having opposite it a number, the first reason being numbered 55 1, for example, the second reason, 2,

the third reason 3, and so on, the space to contain as many reasons for non-payment as a bank may have. In the present instance I have given reason No. 1, as "Account closed"; reason No. 2, "Garnisheed"; reason 60 No. 3, "Dated ahead", etc.

In the present instance and for purposes of illustration I have set up twenty-one reasons and have left a blank space for a further possible reason which may be inserted 65 and numbered 22.

B represents a rectangular space provided with horizontal lines and being sub-divided by vertical lines into smaller spaces C, D, E, F. Above the smaller spaces C, D, E, F 70 respectively appear the words "Drawn on," "Drawn by", "Reason", "Amount".

The space C is to receive the name or names of the bank or banks upon which a dishonored check or dishonored checks are 75 drawn. The space D is for the purpose of receiving the name or names of a person or persons by whom the dishonored checks are drawn. The space E is for the insertion of a key number which refers back to the number opposite the reason for the non-payment 80 of the check appearing in the space A.

The space F is for the insertion of the amounts for which the various dishonored 85 checks may have been drawn.

G is a space for the name of the place where the bank using the form, is located and the date. H is a space for receiving the name of a bank using the form, and I a space for inserting the name of a person 90 or concern to whom the form is addressed.

From the foregoing, the manner of using the form will be apparent. Let us assume that Richard Doe & Sons deposits with the Doe National Bank of Pocatello, a number 95 of checks drawn on New York banks by various customers, for example, by John Doe, Richard Roe, John Roe, etc. The Doe National Bank gives the depositor Richard Doe & Sons, credit for the amount and mails 100 the checks to the Roe National Bank or other banks in New York, which are charged with the amounts of the checks.

The checks are received by the Roe National Bank or other banks and are dishonored for different reasons. Each New York bank holding one or more of the dishonored checks, for example, the Roe National Bank, will fill out one of the forms, giving the reason for the non-payment of 110

the checks and return, by inserting the key number in its proper space, E, the name of the bank on which the check is drawn in its proper space C and the name of the drawer and the amount in their proper spaces D, F. This slip, together with the dishonored check is sent to the Doe National Bank at Pocatello, charging to its account the returned checks.

10 The form is directed to the proper bank by placing the address in the space I.

In practice, I contemplate using my improved form in triplicate and preferably in three colors, let us say white, pink and yellow, and bind them into book form with a weakened line K provided between stubs L and the body of the white and pink forms, so that the latter may be readily detached from the book, while the yellow form, Fig. 2 for example, has no weakened line and is adapted to remain permanently in the book.

The pink and yellow forms are designed to be carbon copies of the original or white form, which has been forwarded with the dishonored returned checks, the first carbon copy or pink form to take the place of the returned check in the New York banks files to show the proper charge, and the second carbon copy or yellow form to remain in the book for permanent reference.

The Doe National Bank receives the returned checks and return forms and at once fills out a form A', Fig. 2, which is substantially identical with the form just described, but in this case is directed and sent to Richard Doe & Sons, the dishonored checks being listed as heretofore set forth, and the key numbers inserted showing the reasons for non-payment.

40 At the end of a month or other stated period, the pink form or first carbon copy of A' is sent to Richard Doe & Sons with the statement rendered by the bank, showing that Richard Doe & Sons' account was debited in the amount of the returned dishonored checks. The second carbon copy or

yellow form, remains in the book as a permanent reference.

Of course instead of having the triplicate sets of forms of different colors, other differentiating means, such as numbers or letters may be employed.

Some of the special advantages gained by the use of my invention, are that by means of the key numbers, it is possible to designate any reason known in banking, as the one for returning the check unpaid, and with a minimum amount of writing, labor and employment of time.

It is also true that my invention makes it possible to use one form for several returned checks, thus effecting a saving of labor, time and stationery.

The use of this form in triplicate as described, tends to exclude the commission of errors, and provides a complete permanent record of the transaction.

What I claim and desire to secure by Letters Patent is:—

1. A banking form, comprising a body portion provided with a space containing reasons for the non-payment of a check presented to a bank for payment, each of said reasons being provided with a key number and a space for inserting the key number which refers back to the specific reason for the non-payment of said check.

2. A banking form provided with the name of a concern using it, a dating space, a list of possible key numbered reasons for the non-payment by a bank of a check presented to a bank for payment, delineated spaces for receiving respectively the name of the bank on which a check is drawn, the name of the drawer of the check, the key number of the specific reason for non-payment, the amount of the check, and a further delineated space for receiving the name of an addressee.

In testimony whereof I affix my signature. 90

JOSEPH PRIMBS.
